RADIATOR VALVE

Filed July 8, 1932

UNITED STATES PATENT OFFICE

CHRISTOPHER G. THIBODEAU, OF ARLINGTON, MASSACHUSETTS, ASSIGNOR TO FRANK W. ZINN, OF BOSTON, MASSACHUSETTS

RADIATOR VALVE

Application filed July 8, 1932. Serial No. 621,409.

This invention relates to a radiator valve structure controlled by a thermostat within the casing element of the structure to provide a vent for the escape of air from a radiator, and permit the closing of the vent to prevent the escape of hot fluid, such as steam or vapor following the air.

The chief object of the invention is to provide a simple, durable, and efficient valve structure, adapted to be automatically conditioned to cause a slower venting of air by a heating medium under relatively low pressure, than by a medium under higher pressure, for a purpose hereinafter appearing.

The term "fluid" used herein is intended to mean either air, steam, vapor, or water.

Of the accompanying drawing forming a part of this specification,—

Figure 1 is a sectional view of a valve structure embodying the invention.

Figures 2, 3 and 4 are views similar to Figure 1 showing different conditions.

Figure 5 is a section on line 5—5 of Figure 1.

Figure 6 is a perspective view of the automatic valve.

Figure 7 is a perspective view of the baffle plate.

Figure 8 is a side view of the wafer valve.

Figure 9 is a side view, and Figure 10 an edge view of the thermostat.

Figure 11 is a side view of the wafer valve flexing member.

The same reference characters indicate the same parts in all of the figures.

The casing of the valve structure includes a base section 30, a head section 31 and an intermediate section 32, said sections being separately connected at 33. The base section 30 has an inlet adapted to communicate with a heating system, said inlet, called the primary inlet, including the bore of a nipple 34.

In the centre of the head section 31 is an inner duct portion 35 with which is associated an automatic valve 36, and other duct portions controlled thereby as hereinafter described.

The casing is subdivided by a partition 44 into an upper chamber 45 and a lower chamber 46. A duct 47 formed in the center of the

partition constitutes an inlet for the upper chamber and an outlet for the lower chamber, said duct being called the secondary inlet.

The lower chamber 46 is adapted to receive water of condensation that may pass through the primary inlet, and is provided with means for preventing such water from entering the upper chamber 45 and escaping from the outlet thereof, said means including a float 48 adapted to be raised by water entering the lower chamber, a valve 49 having a stem 50 fixed to the float, and a seat 51 for said valve in the secondary inlet 47.

Water entering the lower chamber raises the float before it can rise to the upper chamber 45, and thereby closes the valve 49 on its seat.

The secondary inlet 47 extends through a guide 52 on the partition 44, the valve stem 50 being movable in said guide.

In the lower portion of the chamber 46 is fixed a baffle plate 53 supporting the float when the valve 49 is opened.

The float 48, when in its lowest position, may bear directly on the fixed baffle plate 53. I prefer, however, to interpose a supplemental thermostat, designated as a whole by 41, between the float and the baffle plate, said thermostat being constructed like the thermostat 40, above described, and inverted so that its mid length portion 60 bears on the bottom of the float 48, and its arms 61 bear on the baffle plate. The lower end of the float is guided by a spindle 54 fixed to the bottom of the float and movable in central holes in the baffle plate and in the thermostat 41. Said plate is formed to permit fluid to flow across its margin to the chamber 46, and is preferably substantially square as shown by Figure 7, its corners being in close binding contact with the wall of the lower chamber.

55 designates a thin, flexible, resilient metallic wafer valve constituting both an inlet valve and a sealing member adapted to maintain vacuum in the heating system as hereinafter explained. Said wafer valve bears loosely at its marginal portion on an annular valve seat 56 formed on the upper surface of the partition 44, and is adapted to be forced upward and opened by fluid pass-

85

100

ing through the secondary inlet 47, and thereby permit the discharge of air from the heating system.

A flexing member 57 supporting the thermostat hereinafter described, rests loosely on the wafer 55, and is vertically movable in the casing. The margin of the member 57 is substantially square, as shown by Figure 11, and has corners slidable on the wall of the 10 chamber 45, and straight edges between the corners permitting fluid to flow upward across the margin of the flexing member. Said member has a convex bottom face 58 bearing on the center of the wafer 55, and 15 adapted to flex the wafer from the flat form shown by Figure 2 to the concavo-convex form shown by Figures 3 and 4.

The partition 44 has a central depression 59 on its upper side into which the wafer is 20 flexed when the above mentioned thermostat is expanded. Said thermostat, shown separately by Figures 9 and 10, and designated as a whole by 40, is preferably a laminated strip composed of different metals such as 25 brass and steel, the strip being preferably coated with tin. The strip is bent to form a helix having a flat side composed of the mid length portion 60 of the strip, and flat sided arms composed of the end portions 61 30 of the strip. The mid length portion 60 bears on the upper side of the flexing member 57. The thermostat is provided with an orifice 63 (Figure 9) receiving a stud 64 on the flexing member 55, so that horizontal 35 displacement of the thermostat is prevented.

When the thermostat is not expanded by heat the end portions or arms 61 are in the same plane and bear on a fixed abutment formed by the head section 31 of the casing, 40 as shown by Figures 1 and 2, the wafer valve 55 being flat and free to be raised from the seat 56. When the thermostat is expanded the arms 61 are oppositely inclined, the thermostat forces the flexing member 57 downward, and said member forces the central 45 portion of the wafer valve 55 into the depression 59, so that it is held closely against the seat 56, and constitutes a valve closing the secondary inlet 47, as shown by Figures 3 and 4.

The arrangement is such that heated fluid admitted through the secondary inlet 47, the thermostat being contracted, raises and passes by the wafer valve 55, and then expands the thermostat, thereby causing the flexing member 57 to press the wafer against its seat and close the secondary inlet 47.

The time required to expand the thermostat and close the secondary inlet 47 is sufficient to permit the expulsion of all air through the vent formed in part by the inner duct portions 35, before the secondary inlet is closed.

Vacuum caused in the heating system after 60 the above described operation confines the

wafer valve 55 on its seat until heat is again admitted at the primary inlet 34. The wafer valve is preferably more flexible at its margin than at its central portion. The increased flexibility may be provided by 70 notches in the periphery of the wafer as shown by Figure 8, said notches permitting fluid to flow across the periphery of the wafer.

The partition may be provided with an annular groove 62 surrounding the valve seat 59, said groove and the bottom of the depression 59 meeting, so that the valve seat is an annular ridge facilitating the formation of a fluid-tight joint when the wafer 55 80 is pressed against the seat.

My application for Letters Patent of the United States filed September 28, 1931, Serial No. 565,419 now Pat. No. 1,870,300, discloses a valve structure similar in many respects to that above described.

The present invention is distinguished from that disclosed by said application first by the fact that the thermostat 40 is seated on a fixed abutment at the top of the upper chamber, and does not act directly on a valve constituting an element of a vent through which air escapes from the casing, and secondly by the automatically variable air vent 95 next described, said vent including the automatic valve 36.

The casing head section 31 is provided with a variable air vent associated with the upper chamber 45. Said vent includes the above mentioned inner duct portion 35 and automatic valve 36, and a plurality of discharging duct portions 70 and 72. The organization of the automatically variable vent is such that the automatic valve 36, constituting an element thereof, is displaceable to a limited extent by air under relatively low pressure to permit a relatively rapid venting through all of said discharging duct portions, and is displaceable to a greater extent 100 by air under higher pressure to restrict the number of discharging duct portions and cause a slower venting.

The duct portions 35 and 70 are of maximum capacity, and between them is formed a 115 duct enlargement 69. The duct portion 72 is of smaller, or minimum capacity, and extends laterally from the enlargement 69. The automatic valve 36 is movable vertically in the enlargement 69, and is normally caused, 120 preferably by gravity (the valve being weighted), to bear loosely on the bottom of the enlargement 69. The upper end of the valve 36 is formed to close the outer discharging duct portion 70, as 125 shown by Figure 2, when the valve is fully raised, said upper end being preferably provided with an annular valve face 73. The valve is provided with external faces 74 between its ends cooperating with the wall of 130

the duct enlargement 69 to form air passages 75 (Figure 5), in said enlargement.

It will be seen that when the valve 36 is partly and not fully raised, it permits simultaneous venting through the discharging portions 70 and 72, and when fully raised permits venting only through the smaller discharging portion 72.

Figure 1 shows the valve structure as conditioned when the structure is inactive, the automatic valve 36 resting loosely on the lower end of the duct enlargement 69.

Figure 2 shows a portion of the valve structure as conditioned when air is being forced by high pressure steam into the upper compartment 45, and before steam enters said compartment, the automatic valve 36 being closed on the upper end of the duct enlargement 69.

Figure 3 shows the valve structure as conditioned when the air has been vented from the casing and the accompanying radiator is suitably heated.

Figure 4 shows a portion of the valve structure as conditioned when the secondary inlet valve 49 has dropped and opened the secondary inlet 47, thereby permitting vacuum in the system to hold the wafer valve 55 in sealing contact with its seat to maintain said vacuum.

When the heating medium is steam at the lowest pressure and the valve structure is conditioned as shown by Figure 1, air forced through the valve structure by the pressure of steam behind it flows through the inner duct portion 35, and partly but not wholly, lifts the automatic valve 36, and escapes freely through the outer discharging duct portion 70, and to a limited extent through the smaller duct portion 72, until steam reaches and expands the thermostat 40 and causes the latter to press the wafer valve 55 against its seat and condition the structure so that when the secondary inlet valve 49 is opened, vacuum is maintained in the system and holds the wafer valve in sealing contact with its seat until heat again enters the lower chamber 46.

The secondary inlet valve 49 is closed only when the float 48 is raised, either by an accumulation of water in the lower chamber 46, or by the expansion of the lower thermostat 41 by steam entering said chamber, the float being thus caused to close the valve 49.

When the heating medium is steam under a higher pressure, air forced through the valve structure by the pressure of steam behind it, entirely lifts the automatic valve 36 and causes its annular face 73 to close on the seat formed by the top of the duct enlargement 69 and close the outer discharging duct portion 70, as shown by Figure 2, so that the air escapes slowly through the smaller discharging duct portion 72, and retards the entrance of steam into the upper chamber 45,

the retardation being sufficient to prevent the expansion of the thermostat 40 until the radiator with which the valve structure is associated is sufficiently heated.

If air forced by high pressure steam were permitted to escape from the valve structure without the above described retardation, steam would enter the upper chamber 45 prematurely, and cause the seating of the automatic valve 36 shown by Figure 2 before the accompanying radiator is sufficiently heated.

The automatic valve 36 when closed as shown by Figure 2, the valve 59 being open, prevents air from rushing through the lower chamber 46 with sufficient force to raise the float 48 and prematurely close the secondary inlet valve 49, before all, or the major portion of the air is vented. The automatic valve 36 therefore controls the valve 48 to the extent last stated.

I claim:

1. A radiator valve structure which includes a casing having a partition, a lower chamber communicating through a primary inlet with a heating system, and an upper chamber communicating through a secondary inlet in said partition with the lower chamber, an upwardly opening wafer valve bearing loosely on an annular seat on said partition, and adapted to be raised by fluid pressure admitted through the secondary inlet, heat responsive means interposed between the wafer valve and a fixed abutment in the upper chamber and normally conditioned so that the wafer valve is free to be opened by incoming fluid, said means including a thermostat seated on said abutment, and expansible by heat to confine the wafer valve on its seat, the structure including also an upwardly closing valve in the secondary inlet, and means in the lower chamber operable by fluid therein to close and permit the opening of said valve, said structure being characterized by said fixed abutment, and by an automatically variable air vent for the escape of air from the upper chamber, said vent including a plurality of discharging duct portions, and an automatic valve controlling said portions, said valve being displaceable to a limited extent by air under relatively low pressure to permit a relatively rapid venting, and to a greater extent by air under higher pressure to reduce the number of discharging portions and cause a slower venting, the automatic valve preventing premature closing of the secondary inlet valve.

2. A radiator valve structure which includes a casing having a partition, a lower chamber communicating through a primary inlet with a heating system, and an upper chamber communicating through a secondary inlet in said partition with the lower chamber, an upwardly opening wafer valve bearing loosely on an annular seat on said parti-

- tion, and adapted to be raised by fluid pressure admitted through the secondary inlet, heat responsive means interposed between the wafer valve and a fixed abutment in the 5 upper chamber and normally conditioned so that the wafer valve is free to be opened by incoming fluid, said means including a thermostat seated on said abutment and expandable by heat to confine the wafer valve on its 10 seat, the structure including also an upwardly closing valve in the secondary inlet, and means in the lower chamber operable by fluid therein to close and open said valve, said structure being characterized by said fixed 15 abutment, and by an automatically variable air vent for the escape of air from the upper chamber, said vent including an inner duct portion communicating with the upper chamber, an outer discharging duct portion, each 20 of said portions having a maximum conducting capacity, a duct enlargement between said portions, a lateral discharging duct portion of minimum conducting capacity communicating with said enlargement, and an automatic 25 valve movable in said enlargement by air pressure, being displaceable to a limited extent by air under relatively low pressure to permit a relatively rapid venting through each of said discharging portions, and to a 30 greater extent by air under higher pressure to close the larger discharging portion, and thereby cause a slower venting through the lateral discharging portion, the automatic valve preventing premature closing of the 35 secondary inlet valve.
3. A valve structure as specified by claim 2, said automatic valve being weighted and free to move vertically in said duct enlargement, and formed at one end to close the outer dis- 40 charging duct portion, said valve having external faces cooperating with the wall of said enlargement to form air passages therein.
4. A radiator valve structure as specified by claim 1, characterized by a supplemental 45 thermostat in the lower chamber, constituting an element of means for closing and permitting the opening of the secondary inlet valve.
- In testimony whereof I have affixed my signature.
- 50 CHRISTOPHER G. THIBODEAU.
